UNITED STATES PATENT OFFICE.

MARCELLUS FRENCH, OF HOUSTON, VIRGINIA.

BALLOON-TORPEDO.

SPECIFICATION forming part of Letters Patent No. 603,182, dated April 26, 1898.

Application filed July 13, 1897. Serial No. 644,430. (No model.)

To all whom it may concern:

Be it known that I, MARCELLUS FRENCH, of Houston, in the county of Halifax and State of Virginia, have invented certain new and useful Improvements in Balloon-Torpedoes; and I do hereby declare the following to be a full, clear, and exact description of the invention, such as will enable others skilled in the art to which it appertains to make and use

to the same.

The object of this invention is to provide means for conveying torpedoes of great destructive power within the lines of an enemy and exploding the same for the destruction of either life or property.

The invention consists of the combination of a balloon, a torpedo suspended therefrom, an explosive charge or disruptive member for destroying the balloon, and means for igniting said charge.

In the drawing forming part of this specification the figure illustrates a balloon with a torpedo suspended therefrom, an explosive charge for bursting the balloon, and a fuse leading to said charge for igniting the same. I have also graphically represented mechanism adjacent to the explosive charge, which may be a time mechanism, for causing the explosion of the charge to destroy the balloon.

I have also represented as an alternative of the fuse and the time mechanism a cord leading to a hammer or friction-fuse, which may be used for short distances by the operator or sender-out of the balloon.

1 is a torpedo, which may be of any suitable shape and dimensions. I have represented the same as in form of a cylinder having a conical lower end 2 and having connected with such lower end a disk or plate 3. This plate is mounted for movement so as to actuate the plunger forming a part of a friction or percussion primer.

4 is a balloon, of any suitable construction and fabric, of a size or carrying capacity sufficient for the purposes of the case—that is, sufficient to carry a torpedo weighing from five hundred pounds to one ton, more or less, as may be desired.

5 is an explosive charge or disruptive member, arranged by preference at the top of the balloon, of such destructive power that upon

explosion it will tear the fabric and cause the balloon to collapse.

6 is a time-fuse, which may be ignited as the balloon is sent up, to reach the disruptive member at a time predetermined by the operator, or in lieu of the fuse 6 a time mechanism 7 may be used, which may consist of clockwork or other regulated mechanism which can be set to cause the explosion of the charge at any time after the mechanism has been adjusted. As an alternative of the fuse and the time mechanism, where the balloon is to be destroyed at short range, a cord or connection 8 may be attached to the balloon and arranged so that it may be reeled off from a spool, and when the balloon has arrived at its proper position above the point of attack the operator may suddenly pull the cord and cause the explosion of the charge and the destruction of the balloon.

In operation I propose to use ordinarily from five hundred to one thousand pounds of dynamite in my destructive torpedo, and when the winds are favorable and after calculating the time it will take the balloon to arrive over the point of attack I set my time mechanism for igniting the explosive charge or disruptive member for the destruction of the balloon and let the balloon go. When the balloon and the torpedo have arrived over the point of attack, the charge explodes, destroys the balloon, and the torpedo falls by gravity, the remnants of the balloon, operating in the manner of a feather to an arrow, insure that the torpedo will fall end on and thereby renders it certain that such torpedo will explode. The explosion of one ton of dynamite at any point will produce destructive effects for one thousand feet in all directions. While this system or method of destruction may be applied to anihilate armies or bodies of men, a principal service will be to use it for purposes of attack off the coasts of an enemy's country. Steamers could transport these torpedoes rapidly to position, and with a stiff wind toward shore hot-air balloons could be used and the torpedoes could be sent and exploded in such way as to destroy any seaport city.

Having thus described the invention, what I claim as new, and desire to secure by Letters Patent, is—

An apparatus for delivering torpedoes to a point of attack, which consists in the combination of a balloon, a torpedo, supporting means between said balloon and said torpedo, 5 an explosive charge or disruptive member for destroying the balloon, and means for igniting the charge.

In testimony whereof I have signed this specification in the presence of two subscribing witnesses.

MARCELLUS FRENCH.
